UNITED STATES PATENT OFFICE.

WALTER D. BUTZ, OF NORRISTOWN, PENNSYLVANIA, ASSIGNOR TO WILDMAN MANUFACTURING COMPANY, OF NORRISTOWN, PENNSYLVANIA, A CORPORATION OF PENNSYLVANIA.

RIB-KNITTING MACHINE.

1,012,982.

Specification of Letters Patent. Patented Dec. 26, 1911.

Application filed September 9, 1910. Serial No. 581,328.

To all whom it may concern:

Be it known that I, WALTER D. BUTZ, a citizen of the United States, residing in Norristown, Pennsylvania, have invented 5 certain Improvements in Rib-Knitting Machines, of which the following is a specification.

My invention relates to that type of rib knitting machines in which the needle cylinder and needle dial are held against rotation, the cylinder cam ring and dial cam ring being the rotating elements.

The object of my invention is to so construct a rib knitting machine of this type 15 as to dispense with the dogs usually employed on the inner side of the needle cylinder and under side of the needle dial for preventing the rotation of said dial. The objection to the use of these dogs is 20 that the knitted web must be drawn between them in its passage from the needles down into and through the needle cylinder and engagement of the fabric with the dogs has a tendency to distort the stitches in the 25 engaging portion of the fabric and to change the appearance of that portion of the fabric, so as to produce a line or streak in the knitted web. This detracts from the appearance of the web but the more serious 30 objection is the compression or distortion of certain of the stitches which interferes with the proper operation of machines for subsequently acting upon the knitted web, if machines require, for their perfect action, 35 uniformity of stitch structure throughout the web.

My invention comprises certain external means whereby the proper position and relation of the cylinder and dial may be maintained without interfering with the free 40 feed of the yarn to the needles.

In the accompanying drawings—Figure 1 is a view, partly in side elevation and partly in vertical longitudinal section, of 45 sufficient of a rib knitting machine to illustrate my present invention; Fig. 2 is a top or plan view illustrating that portion of the mechanism to which my invention particularly relates; Fig. 3 is a view similar 50 to Fig. 1, of certain parts of the machine, illustrating means other than those shown in Fig. 1, for imparting movement to the dial cam ring of the machine, and Fig. 4 is a view similar to Fig. 2, but illustrating

a modified locking means in accordance with 55 my invention.

Referring first to Figs. 1 and 2 of the drawing, 1 represents part of the fixed bed plate of the machine, to which is secured the needle cylinder 2. Mounted so as to 60 be free to rotate on the bed plate 1 is a bevel wheel 3 and upon the latter is mounted the cylinder cam ring 4 which is provided with the usual cams for imparting vertical reciprocating movement to the needles α 65 of the needle cylinder. Mounted upon posts 5 on the bevel wheel 3 is a yoke 6 which is thus caused to rotate with the bevel wheel 3 and cylinder cam ring 4. The needle dial 7, in which is guided the horizontal 70 dial needles γ , is secured to the lower end of a vertical shaft stem or post 9 which passes through a central hub on the yoke 6, and, above the same, is fixedly secured to the means hereinafter described, whereby 75 its rotation is prevented. Above the needle dial 7 is located the dial cam ring 10, which, on its under side, is provided with the ordinary cams for imparting horizontal reciprocating movement to the dial 80 needles γ , this dial cam ring being caused to rotate in unison with the cylinder cam ring by any appropriate means, the means shown in Fig. 1 for effecting this result being an arm 11 projecting from the dial 85 cam ring 10 and having a set screw 12 engaging the yoke 6. The central post 9 has formed therein a groove 13 which is engaged by a split ring 14 secured to the top 90 of a central hub on the dial cam ring 10 90 whereby said dial cam ring, while free to rotate around the post 9, is caused to partake of any vertical movement of said post and consequently rises or falls in unison with any rising or falling movement of 95 the dial 7, resulting from necessary adjustment of the same in its vertical relation to the needle cylinder 2. Fixedly secured in any suitable way to the post 9 above the yoke 6 is the hub 15 of a ratchet wheel 16, 100 with whose teeth engage pawls 17, of which there may be two or more, four of such pawls being shown in the present instance. These pawls 17 are pivotally mounted upon a ring 19 which rests upon the base of a ring or collar 20, the latter in turn being supported upon the flanged base of a sleeve or bushing 21 which surrounds the central

hub of the yoke 6 and is free to turn therewith. The ring 20 is prevented from turning by engagement with any adjacent stationary element of the machine, thus in the 5 present machine I have shown a rod 22 connecting a boss 23 on the ring 20 with a boss 24 on a sleeve 25 which surrounds a vertical rod 26 of the machine, which rod may, for instance, be that for supporting the 10 bobbin or bobbins whereby yarn is supplied to the needles of the machine. The dial cam ring 10 carries one or more yarn guides *w*, for feeding the yarn to the needles, only one being shown in the present machine. The pawls 17 are normally held in engagement with the ratchet teeth 16 by the 15 action of springs 27 mounted upon the ring 19 and pressing upon the backs of the pawls, as shown in Fig. 2, but as, in a machine of 20 this type, it is necessary for the yarn or yarns to rotate with the yarn guide or guides these pawls would, if always in engagement with the teeth of the ratchet wheel 16, prevent such movement of the yarn and 25 I therefore find it necessary to move the pawls in succession out of engagement with the ratchet wheel in order that the yarn may pass between the point of the pawl and the teeth of the wheel. For this purpose I 30 employ a cam 29 secured to and rotating with the central hub of the yoke 6, which cam, as the yoke rotates, pushes back the pawls 17 in succession and permits passage of the yarn, the latter, by preference, running through a perforation 30 in the cam which perforation is continued, as at 31 and 32, through the sleeve or bushing 21 and yoke 6. In order to provide for vertical adjustment of the dial and dial cam 35 ring in respect to the needle cylinder, the upper end of the post 9 is threaded and is engaged by a nut 33 which rests upon the top of the hub 15, whereby turning of this nut in one direction or the other, after free- 40 ging said hub 15 from connection with the post 9, will cause the raising or lowering of said post and of the dial and dial cam ring carried thereby, the hub 15 being secured to the post again after any such vertical adjustment of said post has been 45 effected. In order to permit movement of rotation or partial rotation of the dial in respect to the needle cylinder, as for instance, when it is desired to shog the dial 50 needles in respect to the cylinder needles, the ring 19 can be moved back and forth upon the ring 20 by means of a handle 55 to such an extent as to effect the desired shogging movement of said dial by engagement of the pawls 17 with the ratchet wheel 16. The ring 19 is, in the present instance, vertically confined to the ring 20, by means of screws 34 which are adapted to segmental slots 35 in said ring 19, as shown in Fig. 2. 60 65 A cap 36, by preference, closes the top of

the ring 20, this cap being supported upon the ring 20 or in any other available manner, and the hub 15, nut 33 and upper end of the post 9 are also, by preference, enclosed by a cap 37 secured to the cap 36 and 70 having, in its top, a central aperture 39 for the passage of the yarn on its way to the needles.

In that embodiment of my invention shown in Fig. 3, the hub of the dial cam 75 plate 10 is extended up into the hub of the yoke 6 and secured thereto by means of a set screw 40, thereby dispensing with the arm 11, as a means of transmitting rotary motion to the dial cam plate.

When shogging motion of the dial in respect to the cylinder is not desired, radially guided and spring-actuated locking bolts, such for instance as shown at 41, in Fig. 4, may engage sockets in the hub 15, and take 85 the place of the pawl and ratchet connection shown in Fig. 1, the bolts being successively retracted by the cam 29 in the same manner as the pawls.

I claim:

1. In combination in a rib knitting machine, a non-rotating needle cylinder, a dial, a dial post, cylinder and cam rings, means for rotating the same, a plurality of independently movable locking devices disposed 95 at different points about the dial post for locking the post against movement, cam means for moving the locking devices individually for the passage of the yarn, and a ring shaped member encircling the dial 100 post connected with the fixed frame and connecting together the independently movable locking devices, substantially as described.

2. In combination in a rib knitting machine, a non-rotating needle cylinder, a dial, a dial post, cylinder and cam rings, means for rotating the same, a plurality of independently movable locking devices disposed at different points about the dial post for locking the post against movement, cam means for moving the locking devices independently for the passage of the yarn, and a ring shaped member encircling the dial 110 post connected with the fixed frame and connecting together the independently movable locking devices, and means to turn the ring shaped member for shogging the connected individually movable locking devices 115 for shogging the dial, substantially as described.

3. In combination in a rib knitting machine, a non-rotating cylinder, a dial, a dial post, cylinder and cam rings, means for rotating the same, a plurality of independently movable locking devices disposed at 125 different points about the dial post for locking the post against movement, cam means for moving the locking devices individually for the passage of the yarn, a ring shaped 130

fixed frame member engircling the dial post, a second ring shaped member supported on the first member movably, and connecting the locking devices together for shogging them simultaneously, substantially as described.

4. The combination, in a rib knitting machine, of a cylinder and dial, cylinder and dial cam rings, means for rotating the same, 10 a dial post, a ratchet wheel thereon, a stationary member of the machine carrying a plurality of pawls for engaging said ratchet wheel, yarn guides disposed to feed the yarn between the ratchet wheel and pawls, and 15 means for retracting said pawls in succession in order to permit of the movement of the knitting yarn around the axis of rotation of the machine.

5. The combination, in a rib knitting machine, of a cylinder and dial, cylinder and

dial cam rings, means for rotating the same, a dial post, a ratchet wheel secured thereto, a non-rotating member of the machine, a plurality of pawls engaging said ratchet wheel, yarn guides disposed to feed the yarn 25 between said ratchet wheel and pawls, means for retracting said pawls in succession to permit movement of the knitting yarn around the axis of rotation of the machine, and a pawl carrier movable about the axis 30 of the dial post whereby intermittent movements of partial rotation may be imparted to the ratchet wheel, dial post and dial.

In testimony whereof, I have signed my name to this specification, in the presence of 35 two subscribing witnesses.

WALTER D. BUTZ.
